CLAIM

The ornamental design for an electrical junction box, as shown and described.

DESCRIPTION

FIG. 1 is a perspective view of a electrical junction box embodying the ornamental design of the present invention.

FIG. 2 is a front view thereof.

FIG. 3 is a top view thereof.

FIG. 4 is a bottom view thereof.

FIG. 5 is a left side view thereof; and,

FIG. 6 is a right side view thereof.

The broken-line disclosure in the views is understood to be for illustrative purposes only and forms no part of the claimed design, and where broken lines abut a claimed surface, the broken-line is understood to represent an unclaimed boundary between claimed and unclaimed surfaces.
